TO WILLIAM R. HEATH, OF BUFFALO, NEW YORK.

REGISTER MECHANISM.

1,179,358.

Specification of Letters Patent.

Patented Apr. 11, 1916.

Application filed January 26, 1909. Serial No. 474,295.

To all whom it may concern:

Be it known that I, FREDERICK O. HEUSER, a citizen of the United States, residing at Chicago, in the county of Cook and State of Illinois, have invented a certain new and useful Improvement in Register Mechanism, of which the following is a full, clear, concise, and exact description, reference being had to the accompanying drawing, forming 10 a part of this specification.

My invention relates to register mechanism and has for its principal objects the provision, first, of a novel form of register which is especially adapted for use in connection with a coin-counting machine for indicating the total value of the coins counted,—although, as will appear later, the register readily adapts itself for use in many other connections; second, the provision of 20 what I term a coin-transmitting device for causing the coins to pass one by one from one receptacle to another, so that they may be counted as they are thus transmitted. Also this coin transmitting device may be 25 adapted to actuate an associated shaft as every coin is transmitted, whereby the register is operated to indicate the value of the transmitted coin. These and other objects and uses of my invention will make themselves clear as the specification proceeds.

Referring to the accompanying drawings, wherein like characters refer to similar parts throughout the several views: Figure 1 is a fragmentary view, partly sectional, of a 35 portion of a coin-assorting machine. Fig. 2 is a top view in plan of my coin-transmitting device. Fig. 3 is a cross-sectional view of Fig. 2 on line 3, 3, certain of the parts being shown in full for the sake of clearness. Fig. 4 is a more or less diagrammatic view of the arrangement of parts comprising my new form of register. Fig. 5 is a side view taken on line 5, 5 of Fig. 4, looking in the direction indicated by the arrows. 45 Fig. 6 is a view taken on line 6, 6, of Fig. 4, showing the relative positions of a carrying-wheel and its associated carry-over wheel.

Referring to Fig. 1, where I have shown 50 part of a coin-assorting machine, the base plate 1 has secured thereto at the bottom a series of suitably arranged tubes 2, 3, 4, 5 and 6, adapted to receive, respectively, dimes, cents, nickels, quarters and half-dollars. To the upstanding flange 7 on the 55 part 1 is secured disk 8, provided with an opening 9. A funnel or hopper 10 is secured

to the disk 8 over the opening 9. In the space between the base plate 1 and the disk 8 is movably housed a disk 11, provided with an opening 12. A shaft 13 is rigidly secured to the disk so that rotation of this shaft will revolve the disk 11. The operation of the coin-assorting mechanism thus far described will now be understood. The coins are promiscuously thrown into the funnel 10, while the shaft 13 is continuously rotated by any suitable means. For the sake of illustration, I have shown the shaft 13 geared to the power shaft 14, which is connected with any convenient form of motive power. As the disk 11 is rotated, it will remove the coins one by one out of the funnel by virtue of the coin dropping into the opening 12. The series of tubes 2 to 6 are so arranged in the base plate 1 that as 75 the coin is carried by the disk 11 it will be in alinement with the openings in the tubes. As soon as the coin is opposite the opening of the tube which is intended for it, it will drop into said tube. It will be noticed that 80 the tubes are arranged in the order of their cross-sectional areas, the first tube 2 having the smallest cross-section. Thus, for instance, if a dime should be carried in the opening 12, it will drop into the tube 2 as 85 soon as it is in alinement therewith. However, a quarter would be carried along by the disk until it came opposite the opening in the tube 5, whereupon it would drop into that tube. 90

With this preliminary description of a suitable form of coin-assorting machine, it will be easier to understand the working of my coin-transmitting device which I will now describe, reference being made to Figs. 95 2 and 3. A fixed base plate 15 is provided at the center with a circular recess 16, in which is adapted to move the hub portion 17 of the coin-removing member 18. This member is also provided with a coin-engaging extension 19, which is adapted to move over the surface of the base plate 15, as shown in Fig. 2. At its outer periphery the base plate 15 is provided with a groove or recess 20, which forms a bearing for the 105 annular member 21. This annular member, which is adapted to rotate on the base plate 15, is provided at its outer periphery with two diametrically opposite gear portions 22 and 23. At its inner periphery the annular member 21 is provided with two inwardly extending portions 24 and 25, each having 110

a coin-engaging portion 26. The shaft 27 is secured at one end to the member 18, and at its other end has a gear 28 meshing with a gear 29 on the power shaft 30. Rigidly secured to the shaft 27 beneath the base plate 15 is an arm 31. A lever 32 is pivotally mounted in proximity to the annular member 21, and has a portion 33 extending partly over the annular member 21, as shown in Fig. 2. The lever 32 is also provided with a projecting portion 34 situated beneath the base plate and extending into the path of travel of the arm 31. A spring 35 normally tends to hold the lever 32 against the stop 36.

The operation is as follows: The coins (in the instance illustrated, nickels) having been fed into the tube 4 by the coin-assorting mechanism shown in Fig. 1, the lower coin will rest upon the base plate 15 at the portion indicated by 37 in Fig. 3. As the power shaft 30 is rotated by any suitable means, the coin-removing member 18 will be rotated in the direction indicated by the arrow in Fig. 2, and during its travel it will engage the coin that is protruding from the tube 4 at 37 and carry the same along with it. The coin will be carried along by the extension 19 until the coin abuts against the curved portion 26 of the extension 24 or extension 25, as the case may be. When this occurs, the further carrying forward of the coin by the member 18 will cause the coin to be held between the engaging surface 38 on the member 18 and the correspondingly curved surface 26, with the result that the annular member 21 will be carried along together with the coin by the member 18. As soon as the gear portion 22 or 23 meshes with the gear 39 the latter will be rotated. The number of teeth in the gear portions 22 and 23 is such that when the gear portion will have passed by the gear 39, the latter will have been rotated one complete revolution. The rotation of the gear-wheel 39 is transmitted through the shaft 40 to the gear 41 and from there to the shaft 42 through the gear 43. If desired, a gear-wheel 44 may be mounted on shaft 42 in order to actuate the counting register 45 through the gear-wheel 46. According to this arrangement, every time that one of the gear portions on the annular member 21 passes by the gear-wheel 30, the register 45 is operated to count the coin that is being transmitted. The movement of the coin and the annular member 21 will be continued by the member 18 until the parts are in the position shown in Fig. 2, where the coin 47 is shown in alignment with the opening 48 in the base plate. At this point the arm 31 strikes the projection 34, moving the lever 32 against the action of the spring 35. This movement of the lever 65 in a clockwise direction causes the exten-

sion 33 to give the annular member 21 a quick movement forward by reason of engagement with the pin 49 on the member 21. This sudden forward movement of the annular member 21 releases the coin from between the engaging surfaces 26 and 38, so that the coin drops through the opening 48 in the base plate. A suitable receptacle 50 is arranged beneath the opening 48 to receive the released coin. As soon as the arm 31 has moved by the projecting portion 34 of the lever 32 the latter will immediately be drawn back by the spring 35 against the stop 36. After the coin has thus been removed from the base plate 15 further movement of the annular member 21 will not occur until the coin-removing member has carried the next coin from beneath the tube 4 against the engaging surface 26 of one of the inward projections 24 and 25. When this occurs, the action above described is repeated,—that is to say, the annular member 21 is carried along with the coin by the member 18, the gear-wheel 39 is actuated to operate the counting register 45, and the coin is released when it reaches a position opposite the opening in the base plate.

We come now to the description of my new register which I have shown in Figs. 4, 5 and 6. In order to best explain the operation of this register I have, for the sake of illustration, assumed that each one of the shafts 51, 52, 53, 54 and 55 is arranged to be operated by a coin-transmitting device such as I have just described. Of course, it is to be understood that this assumption is merely for the purpose of showing one of the many uses to which my register may be admirably put. As shown in Fig. 4, the shaft 51 is arranged to be actuated by the coin-transmitting device that takes care of the dimes; or more briefly stated, we shall say that the shaft 51 represents dimes. In the same way the shaft 52 represents quarters, shaft 53 represents half-dollars, the shaft 54 represents nickels, and the shaft 55 represents cents.

The gear 56 on the shaft 51 meshes with the gear 57 on one end of the shaft 58. The other end of the shaft 58 has secured thereto the gear 59, which is one of the side members of the differential set indicated as a whole by 60. The central member 61 of this set meshes with the gear 62 on the shaft 52. The pinion 63 pivoted on the central member 61 meshes upon opposite sides with the side members 59 and 64. The gear member 64 is carried on one end of the shaft 65, while the other end of the shaft carries the gear 66, which forms one of the side members of the differential set indicated as a whole by 67. The central member 68 of this set meshes with the gear 69 carried by the shaft 53. The pinion 70, which is pivotally mounted to the central gear 68 meshes upon opposite sides with the side members

66 and 71. The side gear 71 of the differential set 67 has rigidly secured thereto the gear 72. The gear 73 on the shaft 55 meshes with the large gear 74 fixed to the shaft 75.

5 At its opposite end this shaft carries the side member 76 of the differential set indicated as a whole by 77. The central gear 78 of this differential set engages with the gear 79 fixed to the shaft 54. The pinion 80 pivotally mounted on the central gear 78 meshes upon opposite sides with the side members 76 and 81, the latter being carried by the shaft 82. This shaft also carries side gear 83 of the differential set indicated as a whole by 84. The pinion 85, pivotally mounted in the central gear 86, engages upon opposite sides with the side gears 83 and 87. The side gear 87 has rigidly secured thereto the gear 88.

20 It will be noted that the shaft 52, which is the quarter-shaft, has secured thereto an additional gear member in the shape of a spiral gear 89. This spiral gear meshes with the spiral gear 90 carried on one end of the shaft 91. The other end of this shaft has fixed thereto the gear 92, which engages with the central gear 86 of the differential set 84. I call special attention to this arrangement of having a plurality of transmission connections leading from the shaft 52 for the reason that I consider it to be the most important feature of my invention. It enables me to transfer into the register by a single actuation of the shaft an amount 30 (as twenty-five cents), which is composed of tens and units. The manner in which this is done will become apparent when I describe the operation of the register.

The gear 72 engages with the central gear 40 member 93 of the differential set indicated as a whole by 94. The pinion 95, pivotally mounted in the gear 93, engages with the side members 96 and 97. The side gear 96 has rigidly secured thereto the gear 98. The gear 97 has rigidly secured thereto the carry-over wheel 99. The gear 88 meshes with the gear 100, which in turn engages the gear 101 secured by the side of the units-wheel 102. The wheels 101 and 102 rotate 45 together with the sleeve 103, which also has fixed thereto the carrying-wheel 104. The tens order set is as a whole indicated by 105 and comprises the numeral-wheel 108, the gear 109 and the carrying-wheel 110. These 50 three wheels are mounted to rotate together with their supporting sleeve 111. The hundreds order set is indicated as a whole by 112 and comprises the numeral-wheel 113, the gear-wheel 114 and the carrying-wheel 115. These wheels are mounted to rotate together with their supporting sleeve 116. The thousands order set is indicated as a whole by 117 and comprises the numeral-wheel 118, gear-wheel 119 and the carrying-wheel 120, all mounted to rotate together

with their supporting sleeve 121. The ten-thousands numeral-wheel is indicated by 122 and rotates together with the associated gear-wheel 123. The orders might, of course, be carried further to any desired extent. The carrying-wheel 110 has associated therewith the carry-over wheel 124 mounted on the sleeve 128. This sleeve also carries the gear 129, which meshes with the gear 114 of the hundreds order set. The carrying-wheel 115 has associated therewith the carry-over wheel 130 mounted on the sleeve 131. This sleeve also has fixed thereon the gear 132, which meshes with the gear 119 of the thousands order set. The carrying-wheel 120 has associated therewith the carry-over wheel 133 mounted on the sleeve 134. The other end of the sleeve has fixed thereto the gear 135 in mesh with the gear 123. This arrangement of the different order sets, together with the carry-over sets for carrying the movement of one order set over into the next order set whenever the first mentioned order set passes through zero, is a common construction in register mechanism and needs, therefore, no further explanation.

I might perhaps mention that each carrying-wheel is provided with a tooth 136, as shown in Fig. 6, so that whenever the numeral-wheel of the set to which the particular carrying-wheel belongs passes through zero, the tooth 136 is in the position shown in Fig. 6 with respect to the associated carry-over wheel. From Fig. 6 it will be seen that as the carrying-wheel 115 moves in the direction indicated by the arrow, it will move the carry-over wheel 130 one space, with the result that the numeral-wheel of the next higher order set is moved one space in the proper direction. In order that the movement of all of the numeral wheels be in the same direction, I have interposed an idler 137 between gear 98, which rotates with the gear 96, and the gear 109 of the tens order set.

The operation of the register for summarizing the value of the coins passed through the transmitting devices associated with each shaft is as follows: Let us suppose that the dime-shaft 51 is being actuated upon the passage of a dime through a suitable coin-transmitting mechanism such as that described. The rotation of the shaft will be transmitted to the register over the following path: from gear 56 to gear 57, through the differential set 60, then through the differential set 67 to the gear 72, the central gear 93 of the differential set 94, from there to the gear 98, through the idler 137, and thence to the gear 109 of the tens order set. The gear-ratios in the above described path are such that the actuation of shaft 51 by the passage of one dime will move the numeral-wheel 108 one space,—that is to say,

the distance from zero (assuming the numeral-wheel 108 was at zero) to the number 1. In the same way the actuations of shaft 53 are transmitted to the tens numeral-wheel, except that the gear-ratios in the transmission path between the shaft 53 and the tens numeral-wheel are such that the actuation of the shaft 53 upon the passage of a half-dollar through the associated coin-transmitting mechanism will operate the tens numeral-wheel five spaces. The actuation of the shaft 55 is transmitted to the gear 74, through the differential set 77, through the differential set 84, and from there through the gears 88 and 100 to the gear 101, whereby the units numeral-wheel 102 is operated. The gear-ratios in the transmission-path between the shaft 55 and the gear-wheel 101 of the units order set are such that the actuation of the shaft 55 upon the passage of a cent through the associated coin transmitting mechanism will operate the units numeral-wheel one space. The transmission path from the nickel-shaft 54 to the units-wheel 102 is through the differential set 77, the same as the path described in connection with the shaft 55, except that the gear-ratios are such that the actuation of the shaft 54 by the passage of a nickel through the associated coin-transmitting mechanism will operate the units-wheel five spaces.

The rotation of the shaft 52 is transmitted to the register through a plurality of parallel paths. I use the term "parallel" in this connection not in its mathematical sense, but by way of analogy to its meaning in the electrical art. In the particular embodiment of my register illustrated the movement of the shaft 52 is transmitted through two parallel paths as follows: One path is from the gear 62 through the differential set 60, etc., the same as described in connection with shaft 51. The other parallel path is from the spiral gear 89 to the spiral gear 90, through shaft 91, gear 92, into the differential set 84, and from there into the units-wheel 102, the same as described in connection with shaft 55. The gear-ratios in these two parallel paths are such that the actuation of shaft 52 upon the passage of a quarter through the associated coin-transmitting mechanism will operate the tens-wheel 108 the distance of two spaces through the first of the parallel paths described, while the units-wheel will be operated five spaces through the second of the parallel paths described. The result of this arrangement is that every quarter passed through the coin-transmitting device associated with the shaft 52 is at once indicated on the register at its proper value.

By virtue of the differential sets 60, 67, 77 and 84, the various shafts may be simultaneously actuated and their actuations will

be summated by the differential sets, as is clearly shown in Fig. 4, attention being directed to the arrows which indicate the direction of rotation of the various wheels and pinions. The operation of differential sets of this character being well understood by those skilled in the art, I do not deem further description thereof necessary.

It will be observed that the units order set is connected with the tens order set 75 through the differential gear set 94. The purpose of this, of course, is to permit the operation of the tens numeral-wheel directly by the shaft 52 through one of the parallel paths above described. At the same time, 80 should the units-wheel 102 pass through zero, motion will be transmitted from the carrying-wheel 104 to the carry-over wheel 99, through the differential set 94, and from there into the tens order set. 85

From the above description of the construction and operation of my register as shown in Fig. 4, it will be apparent that the actuations of the several shafts will be summated by the differential sets and transmitted into the numeral-wheels, whereby the register will indicate the total of the values represented by the actuations of the shafts. If, as in the example used, the shafts are actuated by the passage of coins 95 through the associated coin-transmitting mechanisms, the register will indicate the total value of the coins transmitted.

Although the particular embodiment of my register herein set forth has been shown 100 and described in connection with the coin-counting machine, I wish it to be understood that such showing and description is merely for the purpose of facilitating an understanding of my invention. It should 105 be apparent to those skilled in the art that by modifications in the arrangement and construction of different parts, the register will readily adapt itself for uses in various other connections. I, therefore, claim 110 broadly the feature of connecting a shaft with the register through a plurality of parallel paths for the purpose of accomplishing a predetermined result. Furthermore, 115 it will be apparent that certain features of my invention may be used without combining the use of certain other features, as set forth in the appended claims.

I might add with reference to Fig. 4 that for the sake of clearness and simplicity I 120 have omitted to show such mechanical details as would only obscure the figure and as would be obvious to those skilled in the art. Thus, for instance, I have omitted to show the means of support for the various 125 shafts, sleeves, numeral-wheels, etc., these being details that are matters purely of construction and have nothing to do with the invention.

Having thus described my invention, what

I claim as new and desire to secure by Letters Patent is:

1. In combination, a set of suitably ordered numeral members, a differential gear for carrying from the numeral member of one order into the numeral member of next higher order, said differential gear having an intermediate member, means for actuating the first said numeral member, and means for actuating the intermediate member of the differential gear.
2. In combination, a set of suitably ordered numeral disks, a differential gear comprising side wheels and an intermediate wheel of which one side-wheel is connected with one of said numeral disks, and of which the other side-wheel is connected with a numeral disk of next higher order and of which the intermediate wheel is adapted for actuation to drive the numeral wheel of higher order, and a common means for directly actuating one of the numeral wheels and the intermediate wheel of the differential gear.
3. In combination, a set of suitably ordered numeral wheels, a carry-over mechanism for carrying from a numeral wheel of one order into a numeral wheel of next higher order, a differential gear having an idler pinion interposed in said carry-over mechanism, said differential gear having an intermediate member, the motion of the carry-over mechanism being transmitted through the idler pinion of said differential gear, means for actuating the numeral wheel of one of said orders, and means for actuating the intermediate member of the differential gear to operate the numeral wheel of the other order.
4. In combination, a plurality of suitably ordered numeral wheels, a carry-over mechanism adapted to carry from a numeral member of a lower order into a numeral member of a higher order, a differential gear interposed in said carry-over mechanism, said differential gear having an intermediate member, and a common actuating means for directly operating said numeral member of lower order and for concurrently operating the intermediate member of said differential gear.
5. In combination, a plurality of suitably ordered numeral members, a carry-over mechanism adapted to carry from a numeral member of a lower order into a numeral member of a higher order, a differential gear interposed in said carry-over mechanism, said differential gear having an intermediate member, and a common actuating means for directly operating said numeral member of lower order and for operating the intermediate member of said differential gear.
6. In combination, a register comprising suitably ordered numeral wheels and carry-over mechanisms for carrying from one numeral wheel into another, a differential gear comprising an idler pinion interposed in one of said carry-over mechanisms, said differential gear having an intermediate gear, the carrying being transmitted through the idler pinion mounted on the intermediate gear of the differential gear, a plurality of actuating members, all adapted directly to drive a numeral wheel on one side of the carry-over mechanism in which the differential gear is interposed, and a plurality of actuating members all adapted to directly drive one of said numeral wheels on the other side of the carry-over mechanism in which the differential gear is interposed.
7. In combination, a register comprising suitably ordered numeral wheels and carry-over mechanism for carrying from one numeral wheel into another, a differential gear comprising an idler pinion interposed in one of said carrying mechanisms, said differential gear having an intermediate gear, the carrying being transmitted through the idler pinion mounted on the intermediate gear of the differential gear, a plurality of actuating members, all adapted directly to drive a numeral wheel on one side of the carry-over mechanism in which the differential gear is interposed, a plurality of actuating members all adapted directly to drive one of said numeral wheels on the other side of the carry-over mechanism in which the differential gear is interposed, and differential gearing interposed between the actuating members and numeral wheel on one side of the carry-over mechanism through which all of the actuating members of each set act directly to drive the associated numeral wheel.
8. In a totalizer, the combination of suitably ordered numeral wheels, a carry-over mechanism interposed between two of the numeral wheels, a differential gear having an intermediate member interposed in said carry-over mechanism whereby the carrying is transmitted through the idler pinion mounted on the intermediate member of the differential gear and mechanism for transmitting power from a common actuating means directly to one of said numeral wheels of lower order and to the intermediate member of said differential gear.

In witness whereof, I hereunto subscribe my name this 21st day of January, A. D. 1909.

FREDERICK O. HEUSER.
